COMBINATION DIRECTION SIGNAL AND PARKING LAMP

Theodore Ornas, Jr., Fort Wayne, Ind., assignor to International Harvester Company, Chicago, Ill., a corporation of New Jersey

Application March 12, 1957, Serial No. 45,234

Term of patent 7 years

(Cl. D48—32)

FIG. 1

FIG. 2

FIG. 3

FIG. 4

Figures 1 is a front elevational view of a combination direction signal and parking lamp embodying my new design;

Figure 2 is a plan view thereof;

Figure 3 is a rear elevational view; and

Figure 4 is a side elevational view thereof.

I claim:

The ornamental design for a combination direction signal and parking lamp, substantially as shown.
